UNITED STATES PATENT OFFICE

JOHN T. BAKER, OF PHILLIPSBURG, NEW JERSEY, ASSIGNOR TO J. T. BAKER CHEMICAL CO., OF PHILLIPSBURG, NEW JERSEY, A CORPORATION OF NEW JERSEY

PACKING BOX

Application filed June 21, 1928. Serial No. 287,107.

This invention relates to the provision of an improved packing box for bottles especially for nitric acid and the like, and particularly for large bottles and carboys, which 5 will effectively cushion the vertical as well as the lateral jars and jolts incidental to transportation, and have its removable parts positively secured without the use of nails so that the box may be used repeatedly and 10 its period of use materially lengthened.

The especial object of the invention is the provision of a packing box which is simple and practical in construction, strong, durable and efficient in use, and yet inexpensive 15 to manufacture.

For a full understanding of the invention, a detailed description of a construction embodying the invention in its preferred form will now be given in connection with the accompanying drawings forming a part of this 20 specification and the features forming the invention then specifically pointed out in the claims.

In the drawings:

25 Figure 1 is a perspective view with parts broken away and one end of the box cover elevated;

Figure 2 is a top plan view of the box with its cover removed;

30 Figure 3 is an enlarged section on line 3—3 of Figure 2;

Figure 4 is an isometric view of one of the cushioning elements and

Figure 5 is a sectional view of a detail.

35 Referring to the drawings, A is a wooden packing box shown for purposes of illustration as arranged to receive twelve bottles B, which are resiliently supported in any suitable manner, as by excelsior C, which may be 40 of considerable depth as shown.

Above the resilient support C is preferably arranged a lateral thrust member D provided with a circular opening 1 for each of the bottles B, these openings 1 being of 45 the same or approximately of the same size as the bottle so that the lateral thrust of the bottle is distributed along the periphery of the circle, thus decreasing the danger of breakage. This lateral thrust member D 50 may be placed at any height on the bottles,

but may, with advantage, rest upon the resilient support C, so as to further decrease the danger of breakage by engaging the bottles B at or near their bottoms where the glass is thicker and stronger than on its 55 sides.

The thrusts at the upper ends of the bottles B are absorbed by a thrust member E having circular holes 2, one for each bottle B and of sufficient size to allow the passage 60 of the bottle necks and permit the thrust member E to rest upon the shoulders of the bottles, in which position it is preferably secured in order to hold the bottles B down to prevent their coming out of the openings 1 65 in the lateral thrust member D and to absorb the vertical thrust of the bottles should the packing box A be accidentally turned upside down. The thrust member E may be held in place in any suitable manner, but is 70 preferably secured by one or more cleats F which extend across the member E with their opposite ends engaging suitable slots 3 cut in the sides of the box A. The cleats F may be swiveled or pivotally secured to the thrust 75 member E as by swivels 4.

The top of the box is closed by a cover 5 80 detachably secured to the box without the use of nails. For this purpose each end of the box has secured thereto one or more suitably spaced spring rods 7 carrying detents 8 85 which pass through openings 9 in the box ends and engage holes 10 in a cross piece or cleat 11 secured to the box cover 5 adjacent its end. Upon opening the box, it is only 90 necessary to move the detents 8 outward against the action of the spring rods 7 and hold them in removed position by the insertion of a block or wedge 12 as shown in Figures 1 and 2. The free end of the cover 95 is then raised and drawn forward to release the detents at the opposite box end. A reversal of these steps will secure the cover 5 in place.

The depth of the resilient support C and the location of the slots 3 may be such that the space between thrust member E and the cover 5 is sufficient to prevent the bottle stoppers 13 from contacting with the cover and is preferably such as to prevent the loose 100

stoppers 13 dropping out when the bottles are empty and being returned for filling.

It will be understood that the invention is not to be limited to the especial construction and arrangement of parts shown and described, as these may be varied within the invention as defined by the claims.

I claim:

1. In a packing box for bottles, in combination, a resilient support for the bottles, a rigid lateral thrust member having a circular opening, the wall of said opening neatly fitting the bottle periphery and engaging the bottle at its bottom whereby the lateral thrusts thereon are distributed throughout the periphery of the bottle and at the point where the glass is thicker and stronger, a vertical thrust member having a circular opening, the rigid wall of which surrounds the bottle neck without contact therewith and has its lower edge entirely in engagement with the shoulder of the bottle, a cover on the box, and means for securing the vertical thrust member in position with the resilient support under compression and the bottle stopper out of contact with the box cover.

2. In a packing box for bottles, in combination, a resilient support for the bottles, a rigid lateral thrust member having a circular opening, the wall of said opening neatly fitting the bottle periphery and engaging the bottle at its bottom whereby the lateral thrusts thereon are distributed throughout the periphery of the bottle and at the point where the glass is thicker and stronger, a vertical thrust member having a circular opening, the rigid wall of which surrounds the bottle neck without contact therewith and has its lower edge entirely in engagement with the shoulder of the bottle, a cover on the box, means for securing the vertical thrust member in position with the resilient support under compression and the bottle stopper out of contact with the box cover, and means for detachably securing the cover on the box without the use of nails.

In testimony whereof, I have hereunto set my hand.

JOHN T. BAKER.
